UNITED STATES PATENT OFFICE.

GEORG RICHTER, OF STETTIN, GERMANY, ASSIGNOR TO OFFENBAU-GESELLSCHAFT M. B. H., OF MUNICH, GERMANY, A CORPORATION OF GERMANY.

GAS-GENERATING FURNACE.

1,027,154.

Specification of Letters Patent. Patented May 21, 1912.

Application filed August 8, 1911. Serial No. 842,989.

To all whom it may concern:

Be it known that I, GEORG RICHTER, a subject of the German Emperor, and resident of Stettin, Germany, have invented 5 certain new and useful Improvements in Gas-Generating Furnaces, of which the following is a specification.

My invention relates to generating furnaces or the like, and more particularly to 10 the chambers or passages for mixing the heating gases or combustion air in such furnaces, and has for its object to improve the mixture between the combustion air and the heating gases.

15 To insure the most uniform heating of the walls of the gas-generating chambers in gas-generating furnaces, for instance in retort furnaces, the heating gases must be mixed as thoroughly as possible with the air required for their combustion, and combustion must not take place suddenly at the point where the gases meet the air, but in a gradual and progressive manner. According to 20 my present invention this object is attained 25 by providing in the partition which separates the heating flue from the air flue, transverse conduits alternately inclined in opposite directions and provided at their mouths with sharp edges projecting into the flues for 30 the heating gases or for the combustion air. These transverse conduits, which may be straight, stepped or curved, effect a gradual 35 mixing of the heating gases and combustion air under the influence of the draft of the chimney.

My invention also contemplates the arrangement of such transverse conduits, having projecting edges, in other locations, as will be fully set forth hereinafter.

40 My invention is illustrated in the accompanying drawings, in which,

Figures 1 to 3 show in vertical section various forms of flue. Fig. 4 is a vertical longitudinal section of an inclined retort furnace, in which the conduits for supplying the heating gases and combustion air, as well as the heating flues, are provided with transverse conduits. Fig. 5 is a horizontal section on the line A—B of Fig. 4. Fig. 6 shows in section on an enlarged scale a portion of the furnace seen in Figs. 4 and 5. Fig. 7 is a horizontal section on the line C—D of Fig. 6. Fig. 8 is a vertical section on the line E—F of Fig. 6, and Figs. 9 and 10

are two sectional views, similar to Figs. 6 and 7, of a modified construction of the flue.

As will be seen from Figs. 1 to 3, inclined cross flues or conduits 4 are provided according to this invention in the partition 3 which separates the gas flue 1 from the air flue 2, the conduits 4 being inclined in opposite directions in such manner that they rise alternately from right to left and from left to right. Owing to this arrangement of the inclined transverse conduits 4, the draft induced by the chimney acting in the flues 1 and 2, will result in the heating gas being alternately drawn from the flue 1 into the flue 2, and conversely, the air from the flue 2 into the flue 1 through the inclined transverse conduits, and in that way a gradual and complete mixing of the gases and the combustion air is insured. Each transverse conduit 4 is provided at its mouth with a sharp edge 4* which projects into the flue 1 or 2 this edge 4* dividing the current of heating gas or air which strikes it, into thin layers which are deflected into the transverse conduits. The transverse inclined conduits 4 in the partition 3, can either be straight as in Fig. 1, stepped or broken as in Fig. 2, or curved as in Fig. 3, but it is important that they should be inclined alternately in opposite directions, and in that way the heating gases, and the air required for their combustion, should be alternately drawn from one flue into the other, as indicated by the arrows in Figs. 1 to 3.

In the inclined retort furnace shown in Figs. 4 to 8, the arrangement is such that the partitions with transverse conduits built into the heating gas and air supply flues of the furnace, first bring about a preliminary mixing of the heating gas and the air, while owing to the partitions in the bottom portion of the longitudinal heating flues also having inclined transverse conduits formed in them, a thorough mixing of gas and air takes place in the actual heating flues and further there is a completely uniform, gradually increasing combustion of the mixture of gas and air. The heating gases from the producer 5 pass into the chamber 6, and flow through a conduit 7 into a vertical flue 8 into which open the longitudinal heating flues 9 constituted by the lateral walls of two adjacent retorts or chambers 10.

The combustion air after being subjected to preliminary heating in the regenerator 11, passes from the horizontal flue 12 into the bottom portion of the heating-gas supply flue 8 and into the air supply flue 13 which is separated from the flue 8 by the partition 14. In the partition 14 are provided at certain distances perforations 15 by means of which communication is established between the heating-gas supply flue 8 and the air supply flue 13. To effect preliminary mixing of the heating gas and combustion air, partitions 13 or 17 are provided in the bottom portion of the flues 8 and 13, as shown in Figs. 6 to 8, in which partitions are arranged alternate inclined conduits 18 or 19. Owing to this arrangement, the mixture of gas and air formed in the bottom portion of the flues 8 and 13, is carried alternately in the direction indicated by the arrows, and thus subjected to a preliminary mixing. To insure the best possible mixture between the gas and air, and to enable gradually increasing combustion to take place in the heating flues 9, partitions 20 are built into the front portion of the longitudinal flues 9, these partitions being provided with alternately inclined transverse conduits 21. The mixture of gas and air, effected in the bottom portion of the flues 8 and 13 does not therefore burn suddenly at the point where the heating gases meet the air but owing to the perforated partitions 16, 17, this mixture is first subjected to a preliminary mixing then rises in the flues 8 and 13, and by reason of the transverse conduits 21 in the partitions 20 is burned in the heating flues 9 in a gradual and uniform manner. In that way, a very uniform heating of the furnace chambers or retorts 10, between which the heating flues 9 are formed is insured, and such uniform heating is of great importance for the process of distillation which takes place in the retort or chamber, and for the products thus obtained.

In the construction of furnace shown in Figs. 4 to 8, the heating gases escape through a discharge flue 22 arranged at the back of the furnace. Figs. 9 and 10 show a modified construction of the arrangement in which the front portion of the longitudinal heating flue 9 is provided with a partition 24 having two superimposed series of inclined transverse conduits 25 or 26 rising alternately in oppo-

site directions, whereby a thorough mixing of the gases and of the air is insured throughout the whole height of the flue 9.

The alternately inclined transverse conduits 18, 19 and 21 of Figs. 4 to 8, and the like conduits 25, 26 of Figs. 9 and 10, are provided at their inlets with sharp edges of the same character as the edges 4^a of the channels 4 shown in Figs. 1, 2 and 3; in each case, these edges, by projecting into the adjacent channels or flues separated by the partitions 8, 16, 17, 20 or 24 respectively, will as it were cut or skim thin layers from the gas or air or mixture current flowing in such channels or flues, and cause such layers to be deflected into the inclined or oblique conduits or ducts.

It will be understood that my invention is not limited to the actual arrangements above described and illustrated, and that the constructional details may be varied without departing from this invention.

What I claim is:—

1. In gas-generating furnaces, the combination with a heating gas flue and a combustion air flue, of a partition separating said flues from each other and provided with transverse conduits alternately inclined in opposite directions and having at their mouths sharp edges projecting into said flues, said conduits forming connections between the gas flue and the air flue.

2. In a device for producing a uniform mixture of fluids, adjoining flues, a longitudinal partition separating such flues, said partition being formed with oblique transverse conduits connecting said flues at different points of their length and inclined alternately in opposite directions, the partition being also formed with projecting edges at the inlets of said conduits.

3. In a device for producing a uniform mixture of fluids, adjoining flues, a partition separating said flues and provided with oblique transverse conduits connecting said flues, said conduits being inclined alternately in opposite directions and having projecting edges at their inlets.

In testimony whereof I have signed this specification in the presence of two subscribing witnesses.

GEORG RICHTER.
